UNITED STATES PATENT OFFICE

MAURICE C. RYPINSKI, OF EAST ORANGE, NEW JERSEY, ASSIGNOR TO BRANDES LABORATORIES, INC., OF NEWARK, NEW JERSEY, A CORPORATION OF NEW JERSEY

SOUND REPRODUCING DIAPHRAGM

Application filed November 2, 1927. Serial No. 230,642.

My invention relates broadly to sound reproducing apparatus and more particularly to a construction of a sound reproducing diaphragm.

5 One of the objects of my invention is to provide a conical shaped sound reproducing diaphragm of the free edge type having a high degree of rigidity and arranged for the reproduction of musical notes over a broad 10 frequency range.

Another object of my invention is to provide a conical shaped sound reproducing diaphragm of metallic material having means for mounting the diaphragm in such manner 15 that the peripheral edge is free of any positive form of rim support.

Still another object of my invention is to provide a conical shaped sound reproducing diaphragm constructed of thin sheet metal 20 with wire members extending from the apex thereof and forming centering means for the conical shaped sound reproducing diaphragm with respect to an apertured member through which sound is arranged to emanate.

25 A still further object of my invention resides in the construction of a conical shaped sound reproducing diaphragm from thin metal such as beryllium, aluminum, magnesium or other light metal having a free 30 peripheral edge and supported from the apex of the conical shaped diaphragm for the reproduction of sound over the entire musical scale.

My invention will be more fully understood 35 from the specification hereinafter following by reference to the accompanying drawings in which:

Figure 1 is a side elevation of the conical shaped sound reproducing diaphragm of my 40 invention; Fig. 2 is a front view of the sound reproducing diaphragm; and Fig. 3 is a fragmentary view showing the manner in which the centering wires are attached to the body structure of the sound reproducing dia- 45 phragm.

My invention relates to that class of conical shaped sound reproducing diaphragms which are supported from the apex of the dia- 50 phragm and properly centered with respect to a sound aperture in such manner that sound

vibrations imparted to the apex of the sound reproducing diaphragm are reproduced with good tone quality.

I have found that thin metal, such as beryllium may be used in making the conical shaped sound reproducing diaphragm. This material may be very thin, preferably one quarter of one mil. Beryllium is a metal one-third lighter than aluminum and one-fourth more elastic than steel, and is capable of 55 manufacture by electro-deposition. The cone structure when made of beryllium is actually lighter than a similar structure made of paper, as heretofore used in the art. A cone diaphragm of beryllium has several advantages 60 over a paper diaphragm, for it is not subject to atmospheric conditions in the way that the usual fibrous mounted paper diaphragms are. The cone diaphragm of my invention is capable of being made in one piece 65 by the electrolytic method. The diaphragm is of such light weight that it may be readily supported from the apex and centered by means of wire members which may also be of 70 beryllium, preferably but three mils in diameter. The wire members are laid upon the surface of the cone shaped diaphragm and substantially conform to the surface thereof 75 and extend from the apex beyond the peripheral edge and are secured to a suitable frame 80 with respect to which the diaphragm may be mounted.

Referring to the drawings in more detail, reference character 1 represents an electro-magnetic driver with a rod member 2 projecting therefrom. Rod member 2 is driven from the vibrating armature of the electro-magnetic driver 1 and carries apex pieces 3 and 4 at the end thereof between which the conical shaped diaphragm 5 is mounted. 85 The conical shaped diaphragm 5 is composed of electrolytically deposited beryllium in one piece and is not seamed along one side, as is generally the case with paper cones. The cone of beryllium represented at 5 has a free 90 peripheral edge 6, which is positioned adjacent an aperture 7 in the frame 8. The material of the cone 5 is provided with inwardly pressed ribs 9 which extend along the slant height of the cone and form pockets for re- 95

ceiving the wire members 10 which extend from the apex pieces along the slant height of the cone 5 and beyond the peripheral edge thereof as represented at 11. The wire members at 11 pass through the frame 8 at an angle as represented at 12 and around the front of the frame 8 as shown at 13, and are turned back into the frame as represented at 14. The wire members are thus hooked into the frame and serve to center the sound reproducing diaphragm with respect to the frame. The wire members are secured to the body of the cone by a suitable cement which has been illustrated at 15.

15 I have described the conical shaped sound reproducing diaphragm as preferably made from beryllium, but I desire it to be understood that other light weight materials may be used, such as magnesium and aluminum.

20 While I have described my invention in one of its preferred embodiments, I desire that it be understood that modifications may be made and that no limitations are intended other than are imposed by the scope of the 25 appended claims.

What I claim as new and desire to secure by Letters Patent of the United States is as follows:

1. A sound reproducing diaphragm comprising a conical shaped sheet of thin metallic material, ribs formed in said material at spaced intervals and wire members located in said ribs and extending beyond the peripheral edge of said diaphragm, and means 35 connected to said wire members for centering said diaphragm.

2. A sound reproducing diaphragm comprising a conical shaped sheet of metallic material, means for mounting said diaphragm 40 from the apex thereof and imparting sound vibrations thereto, and wire members laid on the surface of said diaphragm and extending in the plane of said diaphragm beyond the peripheral edge thereof, a frame member 45 and a connection between said frame member and the ends of said wire members for centering said diaphragm with respect to said frame member.

3. A sound reproducing diaphragm comprising a conical shaped sheet of metallic material, means for supporting said conical shaped sheet of material from the apex thereof and imparting sound vibrations thereto, said sheet of metallic material being 55 depressed along the slant height thereof, and wire members extending in the plane of said diaphragm from the apex of said diaphragm along the depressions in the surface of the diaphragm and beyond the peripheral 60 edge of the diaphragm, and means connected to said wire members for centering said diaphragm.

4. A sound reproducing diaphragm comprising a conical shaped sheet of material, means for supporting said conical shaped 65

sheet of material from the apex thereof and imparting sound vibrations thereto, and wire members laid along the surface of said conical shaped sheet of material and extending in the plane of said diaphragm from the apex to the peripheral edge thereof and beyond the peripheral edge, said wire members being bent upon themselves, and means engaging the bent ends of each of said wire members for centering said diaphragm. 70 75

In testimony whereof I affix my signature.
MAURICE C. RYPINSKI.
